United States Patent Office

Des. 216,240

Patented Dec. 2, 1969

216,240

PILLOWCASE OR SIMILAR ARTICLE OF BED LINEN

Leonard C. Clementi, Huntington, N.Y., assignor to Cannon Mills Company, Kannapolis, N.C., a corporation of North Carolina

Filed Nov. 25, 1968, Ser. No. 14,660

Term of patent 14 years

Int. Cl. D6—09

U.S. Cl. D92—26

The figure is a plan view of a pillowcase showing my new design, the side opposite thereto being substantially identical. The balance of the pillowcase, being conventional, is shown broken away for convenience of illustration.

I claim:

The ornamental design for a pillowcase or similar article of bed linen, substantially as shown and described.
